UNITED STATES PATENT OFFICE

2,437,432

TOOL

Rene Martines, Cranston, R. I.

Application October 1, 1946, Serial No. 700,438

5 Claims. (Cl. 30—252)

1

This invention relates to a manually operable tool of the type in which manually actuated members are movable toward and from each other by the hand to cause movement of jaws or other operable parts.

One adaptation of this invention is to cutting pliers or the like in which two actuating members are provided for movement toward each other by pressure of the hand. It is well known that when the hand is fully expanded and the thumb and fingers are just grasping two such actuating or handle members that the strongest pressure of which the hand is capable cannot be applied in this position. Further when the hand is fully collapsed or doubled up such greatest pressure cannot be applied. A point between this full expanded and fully closed position of the hand affords a position for most strongly applying pressure upon the handles or actuating members to move them toward each other.

In the use of the tool shown in my co-pending application Ser. No. 506,575, now Patent No. 2,410,889, granted November 12, 1946, the power multiplying means is normally moved into engagement with the steps through which it is applied and if a stroke is desired without the effect of the power multiplying means it is necessary to hold the yoke out of engagement with the step.

One of the objects of this invention is to improve upon the construction of the tool shown in my prior application as above identified.

Another object of this invention is to provide an arrangement so that the multiplying means will not come into action until there is resistance encountered to the movement of the handles toward each other in an amount sufficient to cause a relative movement of a lever which forms a part of the handle.

Another object of this invention is to provide an arrangement so that the power means comes into operation automatically or mechanically when needed but remains out of action when no resistance is offered and a normal movement of the handles toward and from each other is sufficient to operate the device.

Another object of this invention is to provide an arrangement so that the power actuating means will be free throughout the stroke of the handle means unless some resistance to the movement of the members toward each other occurs.

With these and other objects in view, the invention consists of certain novel features of construction as will be more fully described and particularly pointed out in the appended claims.

2

With reference to the accompanying drawings:

Fig. 1 is a top plan view of this invention applied to a pair of cutters shown in closed position;

Fig. 2 is a view similar to Fig. 1 showing the cutters in open position;

Fig. 3 is an edge view of the cutters;

Fig. 4 is a fragmental view similar to Fig. 2 but illustrating parts broken away to show the internal operating mechanism.

Fig. 5 is a perspective view of the link which connects the two operating members.

With reference to the drawings which illustrate the invention as applied to pliers or cutters in which the movable members are pivoted one

member 10 is pivoted to the other member 11 as at 12 so that the jaws 13 and 14 of the members 10 and 11 will move with the members as the members 10 and 11 are relatively swung about the pivot 12. A cutting edge 15 is provided on the jaw 13 while an abutment surface or anvil 16 is provided on the jaw 14 to be engaged by the jaw 13 as the two are brought together.

The actuating member 10 on the opposite side of the pivot from the jaw 13 consists of a handle 20 which is of the same piece of material as jaw 13 or a piece which is integral with the jaw 13. This member 10 carries a ratchet or step element 21 extending from its inner edge toward the other member and providing a plurality of ratchet teeth 22 along its upper surface.

The handle which is carried by the member 11 consists of a lever 25 pivoted as at 26 to the portion 27 of the member 11 so as to rock relative to this member 11 about the pivot 26. The portion on one side of the pivot designated 28 serves as a handle in opposed relation to the opposite handle 20, while the portion 29 on the other side of the pivot 26 provides a short power arm when acting about the pivot 26.

Alignment block 30 engages the inner surface 31 of the lever 25 and the inner surface 32 of the short member 11 so as to cause these to substantially align. This block 30 is loosely mounted upon a pin 33 which is threadedly mounted as at

34 in the handle lever 28 while its head 35 maintains the block in engagement with the pin.

Another pin 36 loosely extends through a hole 37 in the block 30 and is threadingly mounted as at 38 in the lever 28. A head 39 is provided on this pin and a spring 40 is located beneath the head and presses upon the block so as to maintain the alignment relation which the block effects.

A yoke 41 shown in perspective in Fig. 5 is pivoted as at 42 on the power arm 29 and extends across the short member 11 so that its end 43

acts as a pawl to engage any one of the ratchet teeth 22 of the part 21 which extends between the two members 10 and 11. An inclined slot 44 is provided in the short arm of member 11 and a pin 45 which is carried by the yoke 41 extends into this slot. The movement of the power arm 29 against the short member 11 serves to swing the yoke upwardly away from the ratchet teeth 22 in the member 21 and thus maintains the yoke out of engagement with these teeth, during normal operation of the handles 20 and 28 toward each other, thus the power action utilizing these teeth and the increased leverage is not utilized when little or no resistance is encountered.

If however, a sufficient resistance occurs by reason of the toughness of the work 50 (see Fig. 2), then, as shown in Fig. 4 flexing of the lever 25 or movement of this lever 25 about its pivot 26 occurs causing the block 30 to move inwardly, as shown in Fig. 4, and causing the pin 45 to slide down the inclined slot 44 so that the yoke 41 moves its pawl or bridging end 43 into engagement with teeth 22 of the member 21 and thus the multiplication of the pressure by reason of the lever 25 coming into action occurs and delivers an increased pressure upon the work 50 forcing its cutting jaws 13 and 14 toward each other with a much greater pressure than was provided prior to the coming into action of the lever 25.

In this manner the pressure which is required in ordinary operation of a pair of cutter may be utilized but when an increased pressure is required this increased pressure will automatically come into action by continued squeezing of the handle members so as to relatively swing the lever on one of them and apply power through this increased leverage by a yoke swinging into a position to engage and pull upon the other member at the time that the pivotal relation occurs between the lever and the member on which it is mounted.

I claim:

1. In a device of the class described, a pair of members having work engaging jaws at one end thereof, means connecting said members together for movement toward and from each other, one of said members being shorter than the other member, a lever, a pivot mounting said lever intermediate its ends on the shorter member and extending from the shorter member into opposed relation with the longer member to form a hand grip on one side of the pivot and a power arm on the other side of the pivot, resilient means engaging the lever and shorter member and holding said lever so as to move as one with the shorter member until a predetermined resistance is met whereupon the lever will swing on its pivot, means for transmitting movement of said lever about its pivot to said longer member including a link extending between said power arm and longer member and pivoted to one of them and including means having steps fixed to the other of them and so arranged that said link will clear said steps and means responsive to movement of said lever on its pivot to swing said link into engagement into said steps for transmitting movement from said arm to said longer member.

2. A device as set forth in claim 1 wherein said steps are fixed to said longer member on the side thereof toward the shorter member and said pivot is on said power arm.

3. A device as set forth in claim 1 wherein said steps are successively engaged by said link as said members are closed against a resistance sufficient to swing said lever relative to said shorter member.

4. A device as set forth in claim 1 wherein the members are pivotally related.

5. A device as set forth in claim 1 wherein the means to swing the link member is an inclined slot and pin acting between said link and shorter member.

RENE MARTINES.
